(Cl. D7—7)

To all whom it may concern:

Be it known that I, Jacque A. Scheps, a citizen of the United States, residing at Chicago, in the county of Cook and State of Illinois, have invented a new, original, and ornamental Design for a Bowling Shoe, of which the following is a specification, reference being had to the accompanying drawing, forming a part thereof, in which:

Fig. 1 is a plan view of a bowling shoe, and
Fig. 2 is a side elevational view of the same, showing my new design.

The dominant feature of the design consists in a bowling shoe upper presenting a lacing slit of substantial width occupied by a tongue that is crossed at its forward end by a foxing extending about the forepart of the shoe and providing the upstanding walls thereof.

I claim:

The ornamental design for a bowling shoe, substantially as shown and described.
